UNITED STATES PATENT OFFICE.

ALBERT G. KLETT, OF MILWAUKEE, WISCONSIN.

FLY-TRAP.

1,112,538.

Specification of Letters Patent.

Patented Oct. 6, 1914.

Application filed February 1, 1913. Serial No. 745,530.

To all whom it may concern:

Be it known that I, ALBERT G. KLETT, a citizen of the United States, residing at Milwaukee, county of Milwaukee, and State of Wisconsin, have invented new and useful Improvements in Fly-Traps, of which the following is a specification.

My invention relates to improvements in fly traps.

10 The object of my invention is to provide an inexpensive form of device in which the removal of the fly receiving compartment provides a convenient means for access to the other parts of the trap, regard being had 15 for efficiency, economy of space, and maximum capacity in the attraction and trapping of the flies.

In the drawings—Figure 1 is a plan view 20 of a fly trap embodying my invention. Fig. 2 is a vertical sectional view of the same. Fig. 3 is a plan view of the base member and table, drawn to a reduced scale and with the table partially broken away.

Like parts are identified by the same reference characters throughout the views.

A compartment A is preferably in the form of a vertically disposed chamber having a bottom A' and a removable cap A''. This chamber is adapted to enter the open 30 truncated end of a tapered member B, the height of which is preferably less than the height of the chamber A. A base wall C supports the lower end of the tapered member B, and inner walls J support a table J' 35 upon which the base of the chamber A may rest.

The margins of the table are extended at K to form a support for bait pans E, and connect the table with the base wall C which 40 is provided with slots F through which flies may pass into the annular space between the walls J and C, said flies being then permitted to pass upwardly into the space between the tapered member B and the lower portion 45 of the chamber A. Near the top of the tapered member B, the chamber A is provided with a series of apertures G through which the flies may pass from the space M, inclosed by the tapered member B, to the 50 space N within chamber A. The chamber A may be removed from time to time for the extermination of the flies, the dead flies being removed by taking off the cap A''.

When the chamber A is removed from the 55 member B, convenient access is afforded to

the bait pans and also to the annular space inclosed by the walls J and C. The periphery of the chamber A, its cap A'', the member B and wall C are preferably formed of wire netting. The remaining parts may be 60 formed of any material convenient for the purpose.

I claim—

1. The combination of a base provided with supporting flanges, a table supported 65 from the base, a chamber mounted upon said table and composed of reticulate walls, a truncated tapered member supported from the base with its upper margin embracing said chamber, said chamber being provided 70 with apertures communicating with its interior from the space between the chamber and said truncated tapered member, and means for admitting flies to the last mentioned space from the exterior, substantially 75 as described.

2. The combination with a truncated tapered member, composed of wire netting, a chamber also composed of wire netting and adapted to enter the upper end of said truncated member, said chamber being provided with apertures communicating with its interior from the exterior space inclosed by said truncated member, a base provided with apertures for the admission of flies to said 85 last mentioned space, and means for supporting bait pans in a position to attract flies from the exterior through said openings, substantially as described.

3. The combination with a truncated tapered member, composed of wire netting, a chamber also composed of wire netting and adapted to enter the upper end of said truncated member, said chamber being provided with apertures communicating with its interior from the exterior space inclosed by said truncated member, a base provided with apertures for the admission of flies to said last mentioned space, and means for supporting bait pans in a position to attract 100 flies from the exterior through said openings, said chamber being closed at the bottom and being provided with a removable cap, substantially as described.

In testimony whereof I affix my signature 105 in the presence of two witnesses.

ALBERT G. KLETT.
